CLAIM

The ornamental design for a combined water dispenser and container, as shown and described.

DESCRIPTION

FIG. 1 is a top, front, and left side perspective view of a combined water dispenser and container showing my new design;

FIG. 2 is a left side elevational view thereof;

FIG. 3 is a right side elevational view thereof;

FIG. 4 is a front elevational view thereof;

FIG. 5 is a rear elevational view thereof; and

FIG. 6 is an enlarged top plan view thereof.
